BUOYANT DISK

Hans Pfleumer, New Brunswick, N. J., assignor to
 Rubatex Products, Inc., New York, N. Y., a corporation of Delaware

Application October 24, 1944, Serial No. 560,154

2 Claims. (Cl. 9—8)

1

My invention relates to buoyant members, and particularly to buoyant disks for use in floatingly supporting heavy cables, chains and the like.

In various types of marine operation, it is necessary to float a cable or chain over a long distance and to support the same by a series of buoyant members. Where the chain or cable is at intervals to be wound up on and unwound from a drum, the buoyancy members, particularly when they are rigid in form, are subject to severe distorting stresses.

Heretofore, in floating such cables and chains, hard disks of closed cell cellular rubber have been utilized, owing to the fact that such disks have a specific gravity of .125 or lower, while at the same time, owing to the closed cellular structure, any break or marring of the surface of the disk will not result in the absorption of water thereby.

These hard rubber closed cell cellular disks are, however, rather brittle and when the chain carrying said disks is wound up on a drum, the disks slide relative to each other or assume different angular positions with respect to each other and the edges thereof may well be broken.

Thus, for instance, in the case of mine sweepers which are particularly adapted to remove or discharge magnetic mines, the necessary exploding or removing apparatus is dragged behind the mine sweeper on a chain of non-magnetic material, preferably bronze; although stainless steel is at times used for some or all of the chain.

In order to float this chain, a plurality of hard rubber closed cell cellular disks are mounted thereon. These disks generally are of the order of five to six inches in diameter and approximately one to one and one-quarter inches thick and have an opening through the center through which the chain passes. When the chain is wound up on a drum on the mine sweeper, there may be a considerable momentum involved in the chain's drag through the water and the end of the chain may be heavily loaded.

The principal object of my invention is the provision of means for reinforcing the peripheral annular surface of the buoyancy disks.

An additional object is the addition of means for reinforcing the central hole within the disk.

Still another object of my invention is the provision of means for over-all reinforcement of the entire body of the disk.

Another object of my invention is the provision of an annular hoop reinforcement, preferably of wood around the outer annular surface of the disk.

And a further object of my invention is the

2

provision of internal reinforcing means within the body or on the surfaces of the disk serving to maintain the disk and the reinforcing hoop in proper position.

5 Another object of my invention is the utilization of a wood hoop for reinforcing purposes, since the wood is of relatively low density and at the same time is non-magnetic and therefore well adapted to this purpose.

10 In my application Serial No. 404,997, now abandoned, I have shown a method for internally reinforcing a hard rubber strip by means of wire or screen material which serves to reinforce the same throughout the interior of its structure.

15 Also in my application Serial No. 446,069, now Patent No. 2,404,594, issued July 24, 1946, I have shown a means for reinforcing a hard rubber disk against compressive stresses which are exerted principally in an axial direction.

20 In my present application, the principal object is the reinforcement of a rubber disk against diametric distortion and against chafing and grinding stresses at the corner edges and surfaces thereof.

25 Many other objects of my invention should in part be apparent and where not apparent will be pointed out in the following description and drawings, in which:

30 Figure 1 is a plan view showing the face of a reinforcing buoyancy disk made in accordance with my invention.

Figure 2 is a cross-sectional view taken on line 2—2 of Figure 1.

Figure 3 is a cross-sectional view corresponding to that of Figure 2, but showing a modified form of my invention.

Figure 4 is a plan view of a slightly modified form of buoyancy disk.

Figure 5 is a cross-sectional view taken on line 40 5—5 of Figure 4.

Figure 6 is a cross-sectional view of a drum, showing a method for winding a buoyed chain on a drum.

Figure 7 is a cross-sectional view of a modified 45 form of buoyancy disk.

Figure 8 is a cross-sectional view showing the manner in which a chain carrying the disks of Figure 7 may be readily wound on a drum.

Figure 9 is a cross-sectional view of a repair disk segment taken on line 9—9 of Figure 10 showing the manner in which the same is slipped into place on the bushing.

Figure 10 is a view of the repair disk segment 55 of Figure 9 taken from line 10—10 of Figure 9.

Figure 11 is a cross-sectional view of a modified repair disk.

Referring now to Figures 1 and 2, I have here shown a buoyancy disk 10 having a central core 11 of hard closed cell cellular rubber, an outer annular hoop 12 of wood and surface plates 13 also of wood, and a central opening 14 through which the chain may pass.

Preferably the hoop 12 consists of several spiral layers of hard wood riveted together as at 16 and the inner periphery of said hoop is practically round. The surfacing wood circles or disks 13 consist of plywood and notches 18, preferably six in number, spaced 60° apart, are provided to intercept the circumference with rubber.

The hard rubber closed cell cellular disk may be made in accordance with any of the processes set forth in Patents Nos. Re. 21,245 and 2,299,593.

The degree of hardness is controlled as set forth in said patents by the proportion of sulphur which is mixed with the rubber. In one such typical process, a rubber mix containing a sufficient amount of sulphur and other ingredients is placed in an autoclave and subjected to pressure of an inert gas, such as nitrogen, at a pressure of the order of 3000 pounds per square inch, until the rubber mix is fully permeated.

On relaxation of this external pressure, the entrapped gas at high pressure within the rubber mix causes the same to expand. The "set" and expansion of the rubber previous to its final vulcanization are controlled by a partial vulcanization and cooling before the gassing pressure is removed, so that a multitude of minute non-communicating cells are formed. The expansion of the rubber may then be about four times the volume of the original mix without rupturing the cells.

In the chemical blow process gas generating chemicals are mixed with the rubber and similarly partial vulcanization is applied to the rubber mix so that the gas generated by said chemicals may expand the rubber without rupturing the multiplicity of minute closed cells.

In either process full vulcanization takes place after the rubber has fully filled out the final mold.

In the practice of the process for manufacturing the disks of Figures 1 and 2, the wood hoop 12 is placed within the mold, a suitable central member is placed within the mold in order to form the opening 14; and disks 13, having central holes corresponding to the hole 14 are placed above and below the pre-cured rubber 11.

When rubber 11 expands it flows into intimate contact with the hoop 12 and the wood disks 13, pushing them solidly against the heated mold surfaces (one of which may be formed by the press platen) while at the same time portions of the rubber flow through the notches 18, thus binding the wood disks to the wood hoop and filling the interior space homogeneously with closed cell hard cellular rubber core 11.

By this means, therefore, a buoyant disk may be formed having a superior compressive strength by reason of the members 12, 13 and 11 being integrated.

The buoyancy of the disk itself is not decreased in any way since the added wooden hoop and wooden disks are buoyant themselves. Should it be necessary, however, that the over-all dimensions of the final disk be not greater than the over-all dimensions of an un-reinforced disk, then even in that event the relatively low volume

occupied by the wooden hoop and wooden disk do not appreciably detract from buoyancy.

In a slightly modified form shown in Figure 3, I may utilize a single central disk 20 having an opening corresponding to the opening 14 through the buoyant disk. The central disk 20 has a shape like that of the flat thin disks 13 and is also provided with a number of peripheral notches 18 to permit the rubber material to flow therethrough during expansion and vulcanization.

The buoyant member of Figure 3 is also provided with a peripheral hoop 112 like that of Figures 1 and 2. The disk 20 is a tight fit within the hoop 112. In the manufacture of this type of structure, pre-cured rubber discs of equal dimensions and volume are placed on either side of the wood disk 20 and means are provided in the mold passing through the central opening of the combination 11, 20, 111 in order to form the opening 14 for the chain.

When the buoyant disk is completed it consists of the hard cell cellular closed cell disk 111, having the central stiffening core 120 and the stiffening hoop 112. In a slightly modified form 25 of the construction of Figures 1 and 2 which is shown in Figures 4 and 5, in addition to the outer flat wood disks 213, 213 and the hoop 212, all of which have exactly the form shown in Figures 1 and 2, a tube 25, preferably of plastic material, 30 is provided as a lining for the central opening 14 in order to reinforce the corners thereof. This lining may be formed from the rubber material itself, or a plastic tube of any suitable material 35 may be placed in the opening 14 before the complete rubber disk is expanded into final form.

In all of the constructions shown in Figures 1-5, the peripheral edges of the disk are protected against chafing or grinding by reason of their reinforcement by the wooden hoop 12, 112 or 212 as the case may be. The wooden hoop is maintained in appropriate spaced relation and the pressure thereof against the hard rubber core 11, 111 or 211 is relieved by the disks 13, 120 or 213. In addition, as shown in Figures 4 and 5, the edges of the central opening 14 may be protected by a reinforcing tube 25.

While it is preferred that rubber be used as the closed cell expanded cellular material forming the principal body of the disk, any plastic material which may be expanded to a form having a multitude of minute or relatively minute non-communicating cells may be used for this purpose.

By the means herein described, therefore, the 55 grinding, chafing or breakage which may result from slipping or twisting of the disks on the chain is greatly minimized and the buoyant life of the disks is greatly increased.

The reinforcing members, as can readily be seen, resist compressive stresses, the denting of the edges and the chafing of the central hole. In actual practice, when the chain carrying the disks is wound up on a drum, the disks bear against each other and their edges slip, slide and grind against each other, producing additional chafing and distorting forces.

As shown in Figure 6, this type of slipping and grinding, owing to the uneven surface provided by each layer of rolled up disk carrying chain, 70 may be obviated by winding a layer of canvas 40 between each layer of the disk carrying chain which is wound upon the drum 41. As will readily be seen from Figure 6, the winding of the layer of the canvas 40 around each layer presents 75 a smooth surface for the next layer and thus to

a great extent minimizes the destructive forces which may arise from the uneven surfaces on which superposed layers would otherwise be wound.

In the foregoing I have set forth my invention in connection only with preferred embodiments thereof. Variations in the construction and formation of the buoyancy disks as well as in the processes of making the same should now be obvious.

Thus, for instance, where a buoyancy disk is made in the form shown in Figure 4, it may be possible to maintain the internal gas pressure within the cells at an elevated pressure since disruptive expansion of the buoyancy disk owing to the fact that the internal elevated pressure is resisted by the confining effect of the disks 13, the reinforcing tube 25 and the hoop 12.

Such elevated internal pressure may also be utilized in connection with the construction of Figures 1 and 2 but may result, however, in some constriction of the internal diameters of the opening 14. This latter effect may possibly be beneficial rather than adverse since it will ensure a tight fit of the disk on the chain.

Such elevated internal gas pressure within the buoyancy disk will provide an additional cushioning effect against any shocks which would tend to compress or destroy the disk. The process by which such elevated internal gas pressure may be obtained within the disks is more fully described in my applications Serial No. 407,729 which has matured into Patent 2,395,293, and Serial No. 382,378 which has now matured into Pat. 2,422,797.

In Figures 7 and 8, I have shown a slight modification of my novel buoyant disk which will permit the cable or chain on which it is mounted to be cooled by the water in which the disks support it.

The metallic chain or cable tends to be heated by the electrical current flowing therethrough. If the cable is insulated thermally from the surrounding sea water by closely adjacent buoyant disks, the heat generated therein by the current flow will accumulate and will have a softening effect upon the inner portions of the disks which may warp them.

However, in Figures 7 and 8, I have shown a spacing means for the disks so that water may circulate between them and come into closer adjacency to the cable or chain thereby cooling the same.

In Figure 7, I have shown the inner tube 25' extended at 50 to abut against the end of the tube in the adjacent disk and maintain a spacing equal to the length of extension 50 therebetween. The unit of Figure 7 is identical with that of Figure 1 so that elements 312, 313 and 311 thereof correspond to the similar elements 12, 13, 11 of Figure 1.

In Figure 8, I have shown the inner tube 25' extended at both sides at 50' and 50'' so that disk spacing elements will be present on both sides of each disk.

The spacing obtained by element 50 or by elements 50' and 50'' will necessarily increase the friction of the entire cable or chain unit in the water to an extent proportional to the width of the spacing; but this slight increase in friction is compensated for by the enhanced life of the disks.

The extensions 50 (Figure 7) or 50' and 50'' (Figure 8) provide an additional advantage since the cable (indicated by dotted line 60) can now

be wound more readily over reel 42 (Figure 6) without putting any substantial compressive strain on the inner edges of the inner layers of disks, the thrust being absorbed by extensions 50 or 50' and 50''. Accordingly, the bushings 25' or 25'' should be of strong and stiff material.

When the cable or chain is first assembled, the flotation disks are slid over it to the proper position. However, should a disk be damaged, it is necessary to replace it without disturbing the others; otherwise, a completely new assembly operation will be required.

Accordingly, the damaged disk may be cut up and removed. In Figures 9, 10 and 11, I have shown replacement disks which may be positioned over the cable or chain (in place of the removed disk) without affecting adjacent disks.

In Figures 8 and 9, I have shown a repair disk segment. A disk is cut obliquely along plane 62 to produce two similar portions 63 and 64. A cut 65 is made from the center of edge 66 down through bushing 425 and communicating with opening 414. This cut is approximately the diameter of the cable or chain. The two halves 63 and 64 are forced around the cable and surfaces 62 cemented together with, for instance, a self-setting cord rubber cement.

The repair disk segments 63 and 64 may be prefabricated and molded separately (rather than cutting apart a complete disk) and may have the surfaces 62 corrugated or indented to offer a good surface to hold an adhesive. The side surfacing disks 13 (of Figure 1) may be retained, in cut form of course; but the annular hoop 12 (of Figure 1) may be replaced by a hard rubber skin 80. The cut-out portions 65 need not necessarily be plugged up; but plugging wedges shaped to fit them may, of course, be provided; and such a wedge may be cemented in place on the first disk segment (63 or 64) to be applied to the cable or chain; and may, if the disks can be spread slightly, be inserted in the cut-out 65 of the second segment to be applied.

In Figure 11, I have shown a repair disk 70 which is slotted at 71 from the surface through bushing 525 to the opening 514. After the slot 71 is passed over the cable or chain, until the cable or chain is in the opening 14, a filler piece 72 is cemented in the slot 71. Disk 70 may have the side wooden surfacing circles 13 (of Figure 1) but, instead of the wooden hoop 12 (of Figure 1) it will have a hard rubber skin 580.

Many other variations in the construction and process of making my disk should now be obvious to those skilled in the art. Accordingly, I prefer not to be bound by the specific disclosure herein, but only by the appended claims.

I claim:

1. A buoyant disc comprising a main body portion of expanded closed cell cellular hard rubber; a protective cylindrical covering for said body portion; and a stiffening member therefor, extending normal to the axis of said cylindrical covering and in engagement therewith; openings in said stiffening member; said body portion being expanded into position against said covering and said stiffening member; a portion of said body portion passing through said openings in said stiffening member to anchor said stiffening member to said body portion, said protective covering and stiffening member being formed of relatively rigid buoyant material.

2. A buoyant disc comprising a main body portion of expanded closed cell cellular hard rubber; a protective cylindrical covering for said

body portion; and a stiffening member therefor, extending normal to the axis of said cylindrical covering and in engagement therewith; openings in said stiffening member; said body portion being expanded into position against said covering and said stiffening member; a portion of said body portion passing through said openings in said stiffening member to anchor said stiffening member to said body portion, said protective covering and stiffening member being 10 formed of relatively rigid wood.
